UNITED STATES PATENT OFFICE.

JOHN C. HENDRY, OF BOSTON, MASSACHUSETTS.

STEAM FAN-BLOWER.

SPECIFICATION forming part of Letters Patent No. 323,677, dated August 4, 1885.

Application filed July 5, 1884. (No model.)

To all whom it may concern:

Be it known that I, JOHN C. HENDRY, of Boston, county of Suffolk, State of Massachusetts, have invented an Improvement in Steam 5 Fan-Blowers, of which the following description, in connection with the accompanying drawings, is a specification, like letters on the drawings representing like parts.

My invention relates to a fan-blower of that 10 class in which the fan and its actuating mechanism constitute a single piece of apparatus; and it has for its object to make the blower and engine more compact, efficient, and durable than those now in use. In most cases, when 15 the actuating engine and fan have common frame-work or constitute a single apparatus, the engine acts directly on the shaft of the fan, and in such construction the speed of rotation of the fan is limited to the speed that the engine-piston can attain, and it is necessary to 20 have a larger-sized fan for a given capacity or to deliver a given amount of air than it would be if there were no such limitation to the speed of rotation of the fan. When belting 25 or gearing has been employed to increase the speed of the fan-shaft above that of the engine-shaft, the belting has been a source of trouble on account of slipping, and gearing is noisy, and gives trouble on account of wear 30 and resulting improper fitting.

My invention consists in the combination, 35 with a base or frame-work, of a case for the fan mounted on the said base, and with it constituting a single frame-work, and an engine rigidly connected with the said frame-work, so as 40 to be securely held in definite position with relation to the fan, the said engine having an actuating-pulley in the same plane with the pulley on the fan-shaft and of larger diameter, 45 and the blower-case having fastened upon it two intermediate pulleys or idlers over which the belt for transmitting movement from the engine-pulley to the fan-pulley passes, for the purpose of giving increased contact-surface 50 between the fan-pulley and belt in the well-known manner. The idlers are preferably adjustable on the case or frame-work of the blower to facilitate the maintenance of the belt at the proper tension.

55 Figure 1 is a front elevation of a fan-blower

embodying this invention, and Fig. 2 an end elevation thereof.

The blower-case *a*, having the outlet-opening *b* for the delivery of air, and inlet-opening *c* in its side, with a bracket or pedestal, *d*, in 55 the said opening constituting a bearing for the shaft *e* of the fan *f*, may all be of suitable or usual construction, the said case being supported on and rigidly connected with a bed or base, *g*. The said base and the case have rigidly 60 connected with it a supporting-bracket, *h*, for an engine, *i*, of usual construction, actuating a shaft, *k*, provided with a belt-pulley, *m*. The engine frame-work and blower-case or supporting frame-work for the fan-shaft thus 65 constitute a single member or frame-work rigid throughout, and there is no possibility of the shaft *k* and pulley *m* becoming displaced in relation to the fan-shaft *e* and pulley *n* thereon, which pulley is in plane of the actuating-pulley, *m*, and of smaller diameter, so 70 that when the pulleys *m* *n* are connected by proper belting the latter runs at a higher speed than the former, the ratio being preferably about two or three to one. 75

In order to give the connecting-belt *o* between the pulley *m* and *n* the proper amount of frictional contact with the said pulleys, so that it will not require an excessive tension in order to operate without slipping, the said 80 belt is carried over intermediate pulleys or idlers, *p* *p'*, having their bearings in hangers *r* mounted upon plates *t* securely fastened to the case *a*, so that the said idlers will also maintain the proper position with relation to 85 the other pulleys. The hangers *r* are adjustable by means of the set-screws *u*, or equivalents, to enable the belt *o* to be maintained at the proper tension, and when properly adjusted are rigidly secured by bolts *w*, which 90 pass through elongated openings for the hangers to admit of the adjustment.

In a fan-blower constructed as described the fan receives a high speed of rotation with a comparatively low piston speed in the engine, 95 thus enabling an apparatus of much smaller size to deliver a given amount of air than when the engine acts directly on the fan-shaft, and the speed of the latter is consequently limited to the speed that the engine can attain; but 100

the apparatus has all the advantages of one in which the engine acts directly on the fan-shaft—namely, steadiness of operation, compactness and portability, with equal or increased durability.

I claim—

The combination of the base and blower-case fixed thereon forming a single rigid framework, with the fan-shaft and attached pulley and actuating-engine fixed to the base with its pulley-shaft having its pulley below and in the same vertical plane with the fan-shaft pulley and of greater diameter than said pulley, both the said shafts having their bearings on

the said frame-work, the idler-pulleys adjustably connected to the blower-case above the fan-shaft pulley and in the same vertical plane, and the continuous belt running over the several pulleys, in the manner and for the purpose specified.

In testimony whereof I have signed my name to this specification in the presence of two subscribing witnesses.

JOHN C. HENDRY.
